(57) **CLAIM**

The ornamental design for a novelty cord attachment, as shown and described.

DESCRIPTION

FIG. 1 is a right side elevational view of a novelty cord attachment showing my new design;

FIG. 2 is a left side elevational view thereof;

FIG. 3 is a rear elevational view thereof;

FIG. 4 is a front elevational view thereof;

FIG. 5 is a bottom plan view thereof;

FIG. 6 is a top plan view thereof; and,

FIG. 7 is a side elevational view showing the present invention assembled in a preferred environment.

The broken lines are for illustrative purposes only and form no part of the claimed design.

1 Claim, 4 Drawing Sheets

FIG. 1

FIG. 2

FIG. 7
